UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

HEEL-ASSEMBLING MACHINE.

Application filed July 26, 1920. Serial No. 399,002.

To all whom it may concern:

Be it known that I, JOHN F. STANDISH, a citizen of the United States, residing at Winthrop, in the county of Suffolk and 5 State of Massachusetts, have invented certain Improvements in Heel-Assembling Machines, of which the following description, in connection with the accompanying drawings, is a specification, like reference characters 10 on the drawings indicating like parts in the several figures.

This invention relates to the manufacture of shoes and more particularly to machines for assembling heels. For illustrative purposes the invention is described as embodied 15 in an automatic machine for assembling heel sections or lifts and securing them together to form complete heels.

An object of the invention is to provide a 20 machine arranged, without sacrifice of other utility, to assemble leather and rubber heel sections or lifts in such a manner that the heels thus assembled may be used in the manufacture of shoes according to a method disclosed and claimed in Letters Patent of 25 the United States No. 1,288,253, granted December 17, 1918, which covers a method of heelng shoes in which leather and rubber heel sections are permanently secured together in superimposed relation prior to the 30 attachment of the assembled heels to the shoes.

A further object of the invention is the provision of a power-operated machine arranged to assemble and secure together the heel sections or lifts in an expeditious and inexpensive manner and with a minimum of supervision by the operative.

A feature of the invention consists of 40 novel means for taking the heel sections from a plurality of magazines and superimposing them in assembled relation.

Another feature of the invention consists of an improved presser member and associated parts for squeezing together the superimposed sections and for thereafter transferring them to discharging position.

In the illustrated machine separate magazines are provided for the leather and rubber heel sections or lifts. Before these heel sections are placed in the magazines, the upper surfaces of the rubber sections and the lower surfaces of the leather sections may be coated with cement, which is allowed to dry 50

without further handling of the heels. Heel 55 sections in this condition may be inserted in the magazines and as long as two cement coated surfaces do not come together they will feed through the magazines without sticking. From the magazines the sections 60 are transferred to a support on which they are superimposed with the cement covered upper surface of a rubber section in contact with the cement covered lower surface of a leather section. A presser member then operates to squeeze the heels to secure the sections together, picks them up, carries them off, and discharges them at a suitable point.

While the invention is disclosed as embodied in a specific, automatic machine, it 70 should be remembered that this is primarily for illustrative purposes, and that the invention in some of its features is in no way limited thereto; for example, the means for 75 squeezing together the assembled lifts and thereafter transferring them to the point of discharge is in no way limited in its utility to machines in the operation of which the superimposing of the lifts is automatic or even mechanical.

With the above and other objects and features in view the invention will now be described in connection with the accompanying drawings of an illustrative machine, and pointed out in the subjoined claims.

Fig. 1 is a side view, partly in section, and Fig. 2 is a front elevation of a machine for assembling leather and rubber heel sections or lifts;

Fig. 3 is a plan view thereof;

Figs. 4, 5 and 6 are horizontal sections on the lines 4, 5 and 6, respectively, of Fig. 1.

As illustrated the machine is provided with a supporting frame 10 having a deck 12, the latter having an arcuate elevated portion 14 extending from one side to the front of the machine and providing a surface on which the heel sections may be assembled. Supported above this arcuate surface are a pair of magazines 16, 18, which may be of any type suitable to the storage and feeding of the heel sections or lifts. As shown in Figs. 2 and 3 these magazines are adjustably carried, as through screw and slot connections 19, by a bracket 20 upstanding from the deck of the machine. In the illustrated form each magazine is provided with a series of strips 21 carried by suitable frame

members 22 and which guide the heel sections in such a manner as to permit them to feed downward under the action of gravity. As illustrated these frame members 22 are 5 adjustably connected as by screws 24 and springs 26, 28, to accommodate heel sections of different sizes. Each magazine is provided at its lower end with a gate 30 pivoted at 32 to the deck of the machine and normally 10 held beneath the magazine by a suitable torsion spring 34. These gates are provided each with a downturned portion 36 by means of which they may be opened to permit the downward feeding of the heel lifts, as will 15 be hereinafter more fully described.

It may be here noted that the herein disclosed magazine structure is shown primarily for purposes of illustration and that the invention is in no way limited thereto.

20 Suitably supported, as by a bearing 38 carried by the deck of the machine is a shaft 40 mounted so as to be capable of both longitudinal and rotary movement. This shaft is rotatably connected as at 42 to a yoke 44, 25 the latter being connected to a crank 46 driven from any suitable source of power in such a manner as to reciprocate rod 40. To permit relative longitudinal movement of shaft 40 and the yoke 44 in case the machine jams, the shaft 40 may be connected to the yoke 44 through a spring 48, this spring 30 being stiff enough to transmit to the rod 40 sufficient power to operate the machine under normal circumstances but being capable 35 of yielding, nevertheless, in case of excessive strain.

Rigidly connected to the deck of the machine and surrounding the shaft 40 through 40 part of its length is a sleeve 50 provided with a pair of slots each having a straight vertical portion 52 and a spiral portion 54. Surrounding sleeve 50 is a plunger illustrated as in the form of a sleeve 56 and connected with the shaft 40 by means of a pin 45 58 (see Fig. 6) rigidly connected both to the shaft 40 and to the sleeve 56 and having journaled thereon a pair of rolls 60 arranged to travel in the slots 52, 54 so that as the rod 40 is elevated the plunger or sleeve 56 will 50 first be elevated and then rotated. As the shaft 40 is lowered the reverse takes place. The sleeve 56 is provided with a pair of undercut grooves 62 forming a way in which is mounted a bracket 64 having pivoted at 55 its outer end, as shown at 66 in Fig. 1, the presser member 68. Sleeve 56 is provided with a bracket 61 adjustably connected by a screw 63 with a lug formed on bracket 64 so that the vertical position of the latter and of 60 the parts which it carries may be appropriately adjusted.

The presser member 68 is designed to squeeze together heel sections or lifts which have been superimposed upon the support 65 14 and the contacting surfaces of which are

coated with cement. A comparatively light pressure will cause these cemented sections permanently to adhere to one another so that they may be transferred from the surface upon which they have been assembled and 70 handled thereafter as units in the manufacture of shoes.

For the purpose of transferring the assembled heels from the assembling position and discharging them at a convenient place, the presser member 68 is provided with a brad or picker 70 and with a stripper plate 72 surrounding the picker and provided with a pair of springs 74 (Fig. 1) tending to hold the stripper plate at such a distance 80 from the body of the presser member that, as the presser member is lowered to squeeze the assembled heels, the springs 74 will be compressed so that the stripper member 72 is squeezed into contact with the body of the presser member. The picker 70 accordingly penetrates the assembled heel and, since a latch is provided to hold the stripper plate in inactive condition as the presser member is lifted and rotated, the heel is lifted and 90 transferred laterally. At the discharging position there is provided a chute 76 carrying an upstanding trip member 78 for the purpose of tripping the latch which holds the stripper plate in inactive condition so that the stripper plate operates to discharge the heel into the chute. As illustrated, this latch comprises a substantially L-shaped rod 80 (see Figs. 1 and 3) mounted in a sleeve 82 carried by the presser member, the head of the rod normally being held in engagement with a notch 84 formed in the stem 71 of the presser member. This may conveniently be accomplished by a compression 105 spring 86 the arrangement being such that as the presser member moves to discharging position the extremity of rod 80 is thrust against the trip member 78 so that spring 86 is compressed, the head of the rod 80 moves out of the notch 84 and the stripper plate 72 is actuated by springs 74 to push the heel off of the picker 70 so that it drops into the chute and is discharged thereby.

To transfer the heel sections from the magazine to the surface 14 upon which they are to be superimposed, the machine is provided with two automatically operated grippers 88, 90. These grippers are each provided with a pair of pivoted jaws 92 carried by a member 94 adjustably connected as by a bolt 96 and a dove-tail joint 97 with a block 98 journaled on the sleeve 50. Each block 98 is provided with a gear segment 100 rotated through suitable intermediate gearing by a gear segment 102 mounted upon a shaft 104 (Figs. 1, 3 and 4). Sleeve 56 is provided near its lower extremity with a gear segment 105 arranged to engage, whatever the vertical position of the sleeve 56, with an elongated gear segment 107 rigidly connect- 115 120 125 130

ed to shaft 104. Thus as the shaft 40 is rotated it moves the presser member 68 and the grippers 88, 90 in opposite directions so that while the presser member is transferring an assembled heel to the discharge chute, the grippers are moving to their respective magazines to receive heel sections and while they are transferring these sections to the assembling position the presser member is returning empty from the discharge point to a position over the support upon which the heel lifts are to be superimposed. Since the distance from the different magazines to the assembling surface is different, the radii of the different gear elements are so arranged that the gripper which has the further to move will move the faster and that the different grippers will leave their respective magazines simultaneously and will arrive substantially simultaneously at the assembling position. In order, however, to compensate for any inaccuracy in the timing of the arrival of the grippers at the assembling position, each gear segment 102 is mounted loosely upon shaft 104 and is connected thereto by a suitable clutch illustrated as a friction-slip device. Thus in Fig. 1 the hubs 106 of gears 102 are held in frictional contact with clutch members 108 carried by the shaft 104 by suitable springs 110, so that if either of the grippers reaches assembling position before its gearing has quite completed its movement the appropriate clutch will slip and the gripper will remain stationary.

To insure the registration of different heel lifts at the assembling station, a preferably adjustable stop 112 is provided for each gripper beyond which the grippers cannot swing.

The two jaws 88 of each gripper are provided with interengaging gear segments 114 to insure the symmetrical positioning of the jaws as they are moved towards and from one another. Springs 116 connect the jaws of each pair and tend to move them together with a force sufficient to grip a heel and hold it during its traverse from the magazine to assembling position. The arm of each gripper which is next to its magazine is provided with a tail 117 arranged to strike a preferably adjustable stop 118 (Fig. 3) to open the jaws of the gripper as the gripper moves into registration with the magazine so that the jaws of the gripper will be spaced apart a distance somewhat greater than the width of the heel section which is to be received. As each gripper moves into registration with its magazine it strikes the down-turned portion 36 of the gate of the magazine and swings the gate of the magazine out of registration with the heels in the magazine so that the lowermost heel can drop down into the space between the jaws of the gripper.

Beneath each magazine is a supporting surface, either a portion of the deck of the machine or a plate 119 arranged at such a distance from the gate of the magazine as to permit but one heel section to move down into the space between the jaws, the other heel sections following but being retained in the magazine as the gripper withdraws and the gate of the magazine closes under the influence of its spring 34. As each gripper moves out of registration with its magazine its jaws 92 close upon the heel lift under the influence of spring 116 and hold the lift during its movement to the assembling position. At that position the lifts are superimposed, squeezed together by the presser member to cause their cemented surfaces to adhere, lifted and transferred laterally by the presser member with its picker and discharged by the stripper plate into the chute.

Having described my invention, what I claim as new and desire to secure by Letters Patent of the United States is:

1. A heel assembling machine having, in combination, a movable carrier adapted to occupy horizontally separated lift receiving and discharge stations, said carrier comprising a pointed member, means for assembling lifts by moving them laterally into a position beneath the carrier at the receiving station, means for causing relative movement between the carrier and the first-mentioned means to impale the lift assembly upon the pointed member, and means for moving the carrier with the impaled lift assembly to the discharge station.

2. In a heel assembling machine, the combination of a support upon which heels may be assembled, and means for pressing and securing together the lifts upon the support constructed and arranged to transfer the assembled heel laterally from the support to discharging position and there to release it.

3. In a heel assembling machine, the combination of a support upon which heel lifts may be assembled, and means for pressing and securing together the lifts upon the support constructed and arranged to lift the assembled heel from the support, transfer it laterally from the support, and release it.

4. In a heel assembling machine, the combination of means for superimposing a plurality of heel lifts, and means for pressing and securing together the superimposed lifts constructed and arranged to lift each assembled heel, transfer it laterally, and release it.

5. In a heel assembling machine, the combination of a support on which cemented heel lifts may be assembled, a presser member to squeeze the lifts to cause their cemented surfaces to adhere, and a picker carried by the presser member and operable to transfer the assembled heels from the assembling position to a position at one side thereof.

6. In a heel assembling machine, the com-

- bination by means for superimposing a plurality of cemented lifts, a presser member to squeeze the lifts to cause their cemented surfaces to adhere, and a picker carried by the 5 presser member and operable to discharge the assembled heels from the machine.
7. In a heel assembling machine, the combination of a support upon which cemented lifts may be assembled, a presser member, a 10 picker carried by the presser member, and mechanism for causing the presser member to squeeze the lifts to cause their cemented surfaces to adhere and simultaneously to cause the picker to penetrate the heel, and 15 for thereafter causing the picker to move the heel from over the support.
8. In a heel assembling machine, the combination of a support upon which heel lifts may be assembled, and means for pressing and 20 securing together the assembled lifts comprising a plunger, operating mechanism for said plunger, and a presser member carried by said plunger, said presser member being provided with a picker and a stripper ar- 25 ranged to cause the assembled heel first to move with the presser member and thereafter to be discharged therefrom.
9. A machine of the class described having, in combination, a plunger, a presser mem- 30 ber carried thereby, a picker and a stripper carried by the presser member, means to retain the stripper in inactive condition, oper- 35 ating means for said plunger arranged to cause the presser member to squeeze an as- sembled heel and to cause the picker to penetrate said heel and thereafter to lift the heel and transfer it to discharging position, and means to actuate the stripper to discharge the heel.
- 40 10. In a heel assembling machine, the combination of a plunger, a presser member carried thereby and provided with a picker and a stripper plate, means for operating said plunger to cause said presser member to 45 squeeze together a plurality of heel lifts and thereafter to cause said picker member to transfer the assembled heel to discharging position, and means for causing said stripper plate to release the heel from the picker at 50 said discharging position.
11. In a heel assembling machine, a sup- 55 port upon which heel lifts may be assembled, a transfer device to remove the assembled heels, said transfer device being provided with discharge means and a latch to retain 60 said discharge means in inactive condition, a chute, and means arranged to trip said latch to cause said discharge means to discharge the heels into the chute.
- 65 12. In a heel assembling machine, a presser member for squeezing assembled heel lifts to cause them to adhere, discharge means carried by said presser member, a latch to hold 70 said discharge means in inoperative condi- 75 tion, means to move said presser member to

transfer the heel from assembling to dis- 80 charging position, and means arranged to trip said latch as the presser member reaches discharging position.

13. In a heel assembling machine, the 70 combination of a presser member, a picker and a stripper carried thereby, means to move said presser member to press a plu- 75 rality of superimposed heel lifts and there- after to lift and transfer said lifts, a latch for controlling said stripper and operated 80 to hold said stripper in inactive condition by pressing movement of said presser, and means to release said latch at the conclusion of the transferring movement to permit said stripper to discharge the heel from the picker.

14. In a heel assembling machine, a heel transfer device provided with a stripper, a 85 latch for retaining said stripper in inactive condition, a chute, and a stop carried by said chute to trip said latch and actuate said stripper as the transfer device reaches the chute.

15. In a heel assembling machine, the 90 combination of a plurality of grippers, means to supply a heel lift to each gripper, means to cause the grippers to superimpose the heel lifts, and a presser member ar- 95 ranged to squeeze and secure together the superimposed lifts and thereafter to lift and discharge the assembled heel.

16. In a heel assembling machine, the combination of a plurality of magazines for cemented heel lifts, a plurality of gri- 100 piers, means to operate said grippers to cause them each to take a lift from one of the magazines and to superimpose said lifts, and a presser member arranged to squeeze said superimposed lifts into adhering rela- 105 tion and thereafter to transfer the as- sembled heel to discharging position.

17. In a heel assembling machine, the combination of a plurality of magazines for cemented lifts, a plurality of grippers, 110 means to swing said grippers into registration with said magazines arranged to cause each gripper to take a cemented lift from one of the magazines and thereafter to swing said grippers into registration with 115 each other to superimpose the lifts, and a presser member arranged to squeeze said superimposed lifts to cause their cemented surfaces to adhere and thereafter to trans- 120 fer the assembled heels to discharging posi- 125 tion.

18. In a heel assembling machine, the combination of a plurality of magazines, a gripper corresponding to each magazine, and gears arranged to swing the different grippers into simultaneous registration with their respective magazines to receive lifts therefrom, and thereafter to swing the lifts into assembling position.

19. In a heel assembling machine, the 130

- combination of a plurality of magazines, a gripper corresponding to each magazine, gearing arranged to swing the grippers into registration with their respective magazines 5 to receive lifts therefrom and thereafter to swing the lifts into assembling position, and means to lift the assembled lifts from the grippers and transfer them to discharging position.
- 10 20. In a heel assembling machine, the combination of a plurality of magazines, a gripper corresponding to each magazine, and gears arranged to swing the different grippers into registration with their respective magazines to receive lifts therefrom, and thereafter to swing the lifts simultaneously into assembling position.
- 15 21. In a heel assembling machine, the combination of a plurality of magazines, 20 separately movable grippers corresponding to the respective magazines, and gears arranged to swing the different grippers at different rates of speed into registration with their respective magazines to receive lifts 25 therefrom, and thereafter to swing the lifts into assembling position.
22. In a heel assembling machine, the combination of a plurality of magazines, a gripper corresponding to each magazine, 30 and separate gears arranged to swing the respective grippers into registration with their respective magazines to receive lifts therefrom, and thereafter to swing the lifts into assembling position.
- 35 23. In a heel assembling machine, the combination of a magazine, a movable gripper provided with a pair of pivoted jaws, one of said jaws having a tail, and a stop adjacent to the magazine and arranged to 40 engage the tail of the jaw as the gripper is moved into registration with the magazine to open the jaws for the reception of a heel lift from the magazine.
- 45 24. In a heel assembling machine, a plurality of grippers for assembling heel lifts mounted to swing from lift receiving position to assembling position, a stop to prevent movement of the grippers beyond assembling position, and means to swing said 50 grippers from lift receiving to assembling position, said means being provided with friction clutch mechanism arranged to slip in the event of operation of said means after the grippers have reached assembling position.
- 55 25. In a heel assembling machine, a plurality of grippers for assembling heel lifts mounted to swing from lift receiving position to assembling position, a stop to prevent movement of the grippers beyond assembling position, and gearing to swing said grippers from lift receiving to assembling position, said gearing being provided with friction clutch mechanism arranged to slip 60 in the event of operation of the gearing af- ter the grippers have reached assembling position.
26. A heel assembling machine having, in combination, a heel carrier comprising a pointed member projecting downwardly 70 from the under surface of the carrier, means for simultaneously assembling a plurality of lifts beneath the carrier and for impaling the assembly upon the pointed member, and means for thereafter moving the carrier to 75 a delivering station.
27. A machine of the class described having, in combination, a rod, a sleeve surrounding said rod and provided with a slot 80 having a straight portion and a spiral portion, a projection carried by said rod and entering said slot, means to give said rod and said sleeve relative longitudinal motion, said rod and said sleeve being so mounted that one of them is capable of rotary movement, and means for assembling and securing together shoe parts operated by said rod and sleeve and arranged to lift said shoe parts, transfer them laterally, and release them. 85
28. A machine of the class described having, in combination, a rotatable and longitudinally movable rod, a stationary sleeve surrounding said rod and provided with a slot having a straight portion and a spiral 90 portion, a movable sleeve surrounding said stationary sleeve and rigidly connected with said rod by a member passing through said slot, and article handling means carried by 95 said movable sleeve. 100
29. A machine of the class described having, in combination, a rotatable and longitudinally movable rod, a stationary sleeve surrounding said rod and provided with a slot having a straight portion and a spiral 105 portion, a movable sleeve surrounding said stationary sleeve and rigidly connected with said rod by a member passing through said slot, and a presser member carried by said movable sleeve to squeeze assembled heel 110 lifts into adhering relation.
30. A machine of the class described having, in combination, a rotatable and longitudinally movable rod, a stationary sleeve surrounding said rod and provided with a slot having a straight portion and a spiral 115 portion, a movable sleeve surrounding said stationary sleeve and rigidly connected with said rod by a member passing through said slot, and a presser member carried by said movable sleeve and provided with a picker 120 and a stripper.
31. A machine of the class described having, in combination, a rotatable and longitudinally movable rod, a stationary sleeve surrounding said rod and provided with a slot having a straight portion and a spiral 125 portion, a movable sleeve surrounding said stationary sleeve and rigidly connected with said rod by a member passing through said

slot, and a presser member carried by said movable sleeve and longitudinally adjustable with respect thereto.

32. A machine of the class described having, in combination, a rotatable and longitudinally movable rod, a stationary sleeve surrounding said rod and provided with a slot having a straight portion and a spiral

portion, a movable sleeve surrounding said stationary sleeve and rigidly connected with 10 said rod by a member passing through said slot, and a presser member pivotally carried by said movable sleeve.

In testimony whereof I have signed my name to this specification.

JOHN F. STANDISH.
